CLAIM

The ornamental design for a mosquito trap in the shape of a ball having a truncated top and bottom, as shown and described.

DESCRIPTION

FIG. 1 is a front and top perspective view of the present invention;

FIG. 2 is a front view of the present invention;

FIG. 3 is a rear view of the present invention;

FIG. 4 is a left side view of the present invention (with the right side view being essentially the same in mirror image);
FIG. 5 is a top view of the present invention; and,
FIG. 6 is a bottom view of the present invention.

The broken line showing of environment in the drawings is included for the purpose of illustrating only and forms no part of the claimed design.
